UNITED STATES PATENT OFFICE.

RALPH L. NESS, OF CLARKFIELD, MINNESOTA.

WRECKING BAR.

Application filed May 18, 1925. Serial No. 31,053.

To all whom it may concern:

Be it known that I, RALPH L. NESS, a citizen of the United States, residing at Clarkfield, in the county of Yellow Medicine 5 and State of Minnesota, have invented certain new and useful Improvements in Wrecking Bars, of which the following is a specification.

This invention relates to an implement 10 for use when demolishing buildings, and one object of the invention is to provide an implement which is so constructed that it may be used for prying boards loose from supporting beams and is further so constructed 15 that by proper manipulation of the device the boards may be first pried loose from the beams and then entirely freed from the beams.

Another object of the invention is to provide 20 an implement including an operating bar or handle portion and a board-engaging head which includes spaced arms for engaging a board at opposite sides of a supporting beam and a portion for connecting the arms 25 with each other and with the handle, the latter portion being so formed that the head may be not only readily tilted upwardly to lift the board but also tilted transversely after being swung upwardly.

30 This invention is illustrated in the accompanying drawing, wherein

Figure 1 is a perspective view showing the improved implement in use;

Fig. 2 is a side elevation of the improved 35 implement, and

Fig. 3 is a view looking at the implement from the forked end thereof when tilted, the upper portion of the handle being broken away.

40 Referring to the drawing, it will be seen that the implement which may be termed a "wrecking bar" is provided with an elongated bar-like body portion 1. The bar is formed of steel or any other strong metal 45 and has one end portion flattened and bent to provide an arm 2. The arm 2 is disposed at the angle shown so that it may be grasped and the body portion or lever 1 easily swung downwardly when board-engaging means 50 at the opposite end of the body is disposed beneath a board to be lifted. The arm 2 may also be used as a board-engaging element in which case the device would be inverted from the position shown in Fig. 1 and the 55 arm 2 inserted beneath a board or other object which it is desired to lift. At the op-

posite end of the lever from the arm 2, there has been provided a board-engaging head. This head is substantially U-shaped and includes side arms 3 which are spaced 60 from each other a sufficient distance to permit them to straddle a roofing beam of an ordinary thickness. At their upper ends the side arms are connected by a bridge portion 4 which is curved throughout its length and 65 merges into the side arms. The bridge portion of the head is substantially circular in cross section but the arms 3 may be flattened, as shown, and taper towards their free ends so that they may be readily forced beneath 70 a board to be lifted in case the board is nailed upon a flat surface. At a point intermediate its ends the bridge portion 4 is extended rearwardly, the rearwardly extended portion 5 being tapered, as clearly shown 75 in Fig. 1, and gradually merging into the lever or body portion 1. It should be particularly noted that the under face of the rearwardly extending portion 5 is curved longitudinally and transversely, thereby providing a fulcrum which, to some extent, resembles a fragment of a sphere and that this curved fulcrum forming surface merges into the side edge faces of the rearwardly extending portion and also merges into the 80 curved under face of the bridge 4 and rounded end portions of the bridge. This is a very important feature as it permits the wrecking bar to be tilted rearwardly and transversely so that a board engaged by the arms 85 may be very easily pried loose from a roofing beam.

When the wrecking bar is in use and it is desired to pry a roofing board 6 loose from a roofing beam 7, the wrecking bar will be 90 put in place with its bridge portion resting upon the upper face of the roofing beam 7 and its arms 3 extending beneath the board 6 at opposite sides of the beam. The bar may then be grasped intermediate its length and at the bent upper end portion 2 and downward pressure applied so that the bar is swung downwardly and the arms 3 upwardly upon the fulcrum provided by the curved under face of the bridge and rearwardly 95 extending portion 5. As soon as the arms have been swung upwardly a sufficient distance to move the end portions of the bridge out of engagement with the roofing board, a turning movement may be applied to the 100 lever so that a transverse rocking movement will be transmitted to the head and 105

the arms 3 alternately swung upwardly and downwardly. This rocking movement will tend to work the nails loose which secure the board 6 to the beam 7. It will, therefore, be seen that by means of this improved wrecking bar it will be possible to very easily disconnect the boards of a roof or wall from the beams to which they are nailed.

10 Having thus described the invention, I claim:

A wrecking implement comprising a handle bar, and a U-shaped fork at one end of

said handle disposed at an incline thereto, said fork having spaced parallel arms and a curved bridge connecting their upper ends, said handle bar having a widened end portion joined to said bridge intermediate the ends of the bridge and constituting a fulcrum, the under face of said fulcrum being curved longitudinally and transversely and merging into the intermediate and end portions of said bridge, the said end portion of said bridge being circular in cross section.

In testimony whereof I affix my signature.

RALPH L. NESS. [L.S.]
